METHOD AND MACHINE FOR FORMING CORRUGATED TUBING

Peter Duenas and John Duenas, Forest Hills, N. Y.

Application September 14, 1943, Serial No. 502,252

4 Claims. (Cl. 153—71)

1

Our invention relates to the manufacture of corrugated tubing or metal hose for the purpose of conferring flexibility and for such other purposes as may be desired.

In a general way, the invention is applicable to the formation of corrugations of helical, circular or other circumferential form, but it is more particularly applicable to the formation of the helical type of corrugation on metal tubing.

In a known process of forming helical corrugations in metal tubing, the tubing is passed through an unyielding forming die by a composite rotary and longitudinal movement, the die having a corrugation-forming thread or helix increasing in height and decreasing in pitch in the direction in which the tube progresses through the die. An inner mandrel or core limits the inward displacement of the metal wall and hence the inner diameter of the corrugation, while the die is so formed as to limit the outer diameter of the corrugations to the outer diameter of the tube in which the corrugations are being formed. In such process, the deformation of the metal both inwardly and in axial direction to form the corrugations is opposed at one and the same time by the internal resistance of the metal to deformation and the friction of the inner and outer surfaces of the metal wall with the forming die and the mandrel or core. The force necessary to overcome the external friction and the internal resistance must necessarily be transmitted by the tube itself. This limits the power which can be delivered at the locus of the forming operation, and hence restricts commercial production of corrugated metal tubing of a given metal or alloy to quite limited diameter, wall thickness and depth of corrugation.

An important object of the invention is to facilitate the commercial production of corrugated metal tubing and make possible the production of same in greater dimensions such as diameter, depth of corrugation and wall thickness. Incidental to the attainment of these objects, it becomes possible within the principles of the invention to readily produce corrugated metal tubing of given dimensions of metals and alloys which have not heretofore been susceptible of forming into corrugated shapes, for example steel tubing of comparatively heavy walls and large diameter.

According to our invention, the power necessary to displace the metal inwardly and in an axial direction to form the corrugations is transmitted only in part by the turning of the tube, and the surface friction is greatly reduced, so

that it becomes possible to commercially produce corrugated metal tubing of much greater size, wall thickness and depth of corrugation. This result is accomplished by the application of intermittent pressure inwardly against the tube wall by a yielding die member actuated by power-driven vibratory means while feeding the tube through the die in a rotary and axial direction. The inward displacement of the metal is thus

accomplished by direct inwardly-applied vibratory pressure, and the axial displacement is accomplished by the turning of the tube within the die under conditions of greatly reduced surface friction. To facilitate this operation, the die employed for the forming operation must be in at least two parts, and preferably three or more parts, no one part being more than 180° in circumference, and preferably somewhat less. The die parts are complementary, and one is movable with respect to the other in a direction to open and close upon the metal tube passing through the die during the forming operation. This opening and closing motion is effected transversely of the wall of the tubing, and need be little more than sufficient to alternately grip and free the contacting surfaces of the tubing and moving die part.

An illustrative embodiment of the invention is represented in the accompanying drawing, in

30 which—

Figure 1 is a longitudinal elevation of a machine with a length of tubing in the course of being processed.

Figure 2 is an enlarged vertical section of the forming die mechanism shown in Figure 1.

Figure 3 is a side elevation of the forming die mechanism shown in Figure 2, and

Figure 4 is an enlarged detail elevation of the tubing, with parts in section, illustrating the development of the corrugations in the tubing as it passes through the forming die.

Whereas the invention is applicable in a broad sense to the production of either helical or strictly circular corrugations, the machine selected for purposes of illustration is designed for the formation of a helical corrugation in metal tubing, it being, of course, understood that other types of mechanism capable of performing substantially the same operations may be employed within the scope of our invention.

As seen in Figure 1, the machine embodies the track bed 10 mounted on feet 11 and the forming die bed 12. There is provided carriage 13 free to move along the track 10 on the rollers 14 and fitted with the hollow spindle 15 which is driven

by motor 16 through speed reducer 17 and gears 18 and 19. The hollow spindle 15 has mounted thereon a tube-gripping chuck 20 which may, for example, be in the form of a three-jawed scroll chuck or a four-jawed independent chuck, the essential requirement being that it be capable of firmly gripping the outer wall of the tubing 21 to effect its rotation within the forming die, as will be further explained. A guide bearing 22 may be mounted on a pedestal or foot 23 in position to support and align the tubing as it issues from the machine, and a guide bearing 24 supported on the adjustable pedestal or foot 25 may guide the tubing on its way to the forming mechanism, which will now be described.

The forming die bed 12 may be in the form of a casting having the side frames 26, 27 integrally united or otherwise joined across the top by the cross member or block 28, as clearly illustrated in Figures 2 and 3. The side frames 26, 27 provide bearings for a shaft 29 driven by the belt pulley 30 of the vibratory apparatus. Shaft 29 has keyed thereon a cam wheel 31 of waved contour to engage a roller 32 which is mounted on a shaft 33 journaled in the arms 34 of a U-shaped plunger 35. The plunger 35 has grooved sides 36, 37 which slide up and down on tracks or ways 38, 39 vertically mounted on the side frames 26, 27 of the forming die bed 12. The plunger 35 is thus free to move up and down in a vertical path between the side frames 26 and 27. Compression springs 40, 41, which may be guided on vertical pins or rods 42, 43 mounted in the bed member 12, normally urge the plunger 35 upward but yield to the downward movement of the plunger under the influence of the cam wheel 31 upon the roller 32, the plunger 35 being provided with suitable bores 44, 45 to freely receive the upper ends of the rods 42, 43.

The lower forming die member 46 may be secured to the forming die bed 12 by countersunk bolts 47, 48, and the upper forming die member 49 may be secured to the under surface of the plunger 35 by countersunk bolts 50, 51. Only two die parts are shown to illustrate the principle of a yielding die member which may be actuated by suitable mechanism to intermittently open and close the die while the tubing is being passed therethrough.

For the formation of a helical corrugation, the plurality of die members may carry complementary portions of the corrugation-forming rib or helix, as apparent from Figures 2 and 3 of the drawing. The form of this rib or helix may, if desired, be such as to produce a helix of somewhat larger outside diameter than the original tube which is being corrugated. At the entrance to the die, the forming rib is of shallow depth or height and relatively great pitch, and as it progresses toward the exit, the height or depth increases and the pitch decreases. Thus, as seen in Figure 2, the forming thread or rib starts at 52 as a shallow or low rib of high pitch and proceeds through the stages 53, 54 and 55 to the stage indicated at 56, the first turn marking a portion of the tube length which is to constitute one corrugation, and the successive turns operating upon the metal to displace the trough inward and reduce the axial length while permitting its outer diameter to expand or increase under the axial reduction in length. The inward displacement of the troughs is accomplished largely by the vibration of the die which occurs transversely of the axis, and the displacement in axial direc-

tion occurs largely as a result of the turning of the tube within the die.

In operating the machine, the vibrator is set in motion and a length of tubing 21 is passed through guide 24 into the entrance of the forming die and turned either by hand or by wrench until the end projects through the exit of the die sufficiently to be gripped by the chuck 20. The carriage 13 is moved to the left (in Figure 1) so as to enable the chuck to engage the tube close to the forming die. The motor 16 is then started which rotates the tube continuously at the same time that the die is being vibrated. During this operation, the tube is continuously moving through the die under the influence of the helical corrugations of the forming rib of the die so that the carriage 13 is moved to the right (in Figure 1) toward the tube guide bearing 22. As the carriage approaches this guide bearing, the motor 16 is stopped, the chuck 20 opened, and the carriage bearing the chuck is shifted to a new position on the tube close up to the forming die, whereupon the chuck is again clamped on the tube and the motor started to resume the operation described. In practical operation, the corrugated tube is readily made in any desired length by welding a fresh tube onto the trailing end of each tube as the rear end approaches the forming die, the machine being stopped temporarily for each welding.

The rate of rotation with relation to the frequency of the vibration may be varied. Thus, the tube may be inserted while the die is being vibrated, at, for example, thirty vibrations per second, and after gripping the end of the tube with the chuck 20, the motor may be started and the speed varied while observing the smoothness and ease with which the corrugations are produced, until the point is attained at which the minimum effort and the smoothest operation is obtained, which may occur, for example, in a given case when the circumferential travel of the tube surface amounts to one sixteenth of an inch per vibration. By reference to Figure 4, the deformation or displacement of the metal will be apparent. Between the points A and B, the distance along the surface of the metal should be substantially equal to that between the points B and C, or C and D, or D and E, etc. The vibration of the die creates the depressions illustrated, and the turning of the tube causes the point B to approach the point A, the point C to approach the point B, the point D to approach the point C, the point E to approach the point D, etc., until the last one or two convolutions of the forming rib are reached in the die, whereupon the axial displacement of the metal ceases. The approach of these respective points toward each other in an axial direction has the effect of decreasing the pitch and at the same time increasing the outer diameter of the corrugation. Such an operation would encounter very serious surface friction were it not for the fact that the vibration of the yielding die member intermittently reduces the pressure of contact or frees the contacting surfaces from each other, these operations alternating with the application of the die pressure transversely of the axis to develop the depth of the troughs. While there may be some circumferential flow of the metal due to the continuance of the twisting moment while the vibratory die member is applying the transverse pressure on the tube wall, this effect is believed to be purely incidental, and may be so slight as to be almost negligible. The forming operation completes the

corrugated tube substantially without appreciable change in the wall thickness. The intermittent gripping and freeing of the tube surface during the turning of the tube greatly reduces the drag or friction in the forming operation, and greatly facilitates the passage of the tube through the forming die.

The illustrative example above described obtains relative rotary motion between the forming die and the tube by holding the die and rotating the tube, but it will of course be apparent that the principle involved is the same whether the tube or the die or both be rotated in such way as to obtain turning motion of one with respect to the other.

We claim:

1. Method of corrugating metal tubing which comprises supporting, guiding and rotating metal tubing by the application of supporting, guiding and rotating instrumentalities substantially entirely to the outer wall surface of the tubing, while maintaining the interior of the metal tubing substantially free and unobstructed throughout its length, and simultaneously depressing the troughs and raising the ridges of the corrugations by intermittently applying and releasing metal deforming pressure in the form of a succession of intermittent pressure impulses to the outer wall of the tubing as it rotates.

2. A method of forming corrugated metal tubing which comprises gripping, supporting and applying to the tubing at one portion of its length a rotary driving force leaving the tubing freedom of axial motion, and simultaneously depressing the troughs and raising the ridges of the corrugations by intermittently applying to the outer wall of the rotating tubing at another portion of its length a succession of pressure impulses alternating with pressure releases directed transversely of the tubing axis as the tubing continues to rotate and due to the rotation of the tubing progressing circumferentially around the tubing wall.

3. A method of corrugating metal tubing which comprises depressing the metal wall to a reduced internal diameter by applying metal de-

forming pressure substantially entirely to the outer wall of the tubing in the form of a succession of pressure impulses alternating with pressure releases at a portion of its length free to yield inwardly, and simultaneously gripping and applying to the tubing at another portion of its length a rotary driving force leaving the tubing freedom of motion in an axial direction, whereby the said pressure impulses progress circumferentially of the tubing and the tubing is left free to move axially in response to axial pressure resulting from the application of the metal deforming pressure.

4. Apparatus for corrugating metal tubing comprising in combination a forming die adapted to receive the metal tubing, means for supporting said die and holding it against axial displacement, gripping and rotating means for driving the metal tubing while it is in said forming die, 15 said means comprising a driven hollow spindle and chuck for receiving the metal tubing, and means for supporting and guiding said gripping and rotating means, permitting it to move freely toward and away from said forming die axially 20 of the metal tubing in response to axial pressure applied by the metal tubing.
